UNITED STATES PATENT OFFICE.

WILBER THOMAS, OF QUINCY, ILLINOIS.

FENCE-PICKET.

SPECIFICATION forming part of Letters Patent No. 267,948, dated November 21, 1882.
Application filed July 24, 1882. (No model.)

To all whom it may concern:

Be it known that I, WILBER THOMAS, of Quincy, in the county of Adams and State of Illinois, have invented certain new and useful 5 Improvements in Fence Pickets, Palings, &c.; and I do hereby declare that the following is is a full, clear, and exact description of the invention, which will enable others skilled in the art to which it appertains to make and use 10 the same, reference being had to the accompanying drawings, which form a part of this specification.

This invention relates to fence pickets, palings, and the like; and it consists in certain 15 improvements in the construction and operation of the same.

In the drawings, Figure 1 is a perspective view of a portion of a fence embodying my 20 improvements; Fig. 2, a top view thereof; Fig. 25 3, a detail sectional view of one of the pickets, and Fig. 4 a perspective view showing a former mode.

In this class of fences, where the pickets are held in place by encircling twists of twisted 25 strands of wire, when the wire binds against the smooth ungrooved surface of the picket—such as shown in Fig. 4 of the drawings—water, dust, &c., are held just above the point of contact. The dirt and water collected at this point 30 in time rot and otherwise damage the picket. It has also been practically demonstrated that in fences of this class, when the pickets are ovolu, diamond, rectangular, or of any other cross-section shape that presents a continuous 35 smooth surface to the wire, the pickets become displaced both vertically and laterally, as the wire cannot be twisted around these pickets so as to secure a hold. This displacement entirely destroys the utility of the fence for ornamental purposes, so that it is only useful for 40 farm and the like fencing. These disadvantages it is the object of my present invention to obviate, and also to produce a simple, durable, and efficient fence for ornamental purposes 45 that will vie in point of beauty, excellence, and attractiveness with the iron and like fences now in use, and that can, however, be manufactured at a cost not exceeding that of the same class of fences having smooth-surfaced 50 pickets, which are worthless for ornamental fencing by reason of their sagging and ready displacement. To this end I form the pickets,

which are denoted in the drawings by the letter A, with a series of longitudinal grooves or channels, B, around their entire surface. These 55 channels B extend from end to end, and form or leave intermediate contacted edges or ridges, b.

The twisted loops a of the securing-strands of wire C encircles the pickets in the usual manner; but in the herein-described shape of 60 picket these encircling twists a will, to a certain extent, enter and bind in the intermediate ridges, b, around the entire surface of the picket. By this means the wire binds in the picket in a plurality of places on both side surfaces, and 65 effects the absolute locking in place of the picket, so that sagging or displacement in any direction is obviated. By reason of this shape of pickets, which have a plurality of projecting ridges or points on each side surface, and the 70 relative action of the securing-twists a against these ridges, which effects absolute locking of the picket, I am enabled to produce a fence for ornamental purposes of great commercial value at a cost not exceeding that of the com- 75 monest form of ornamental fencing, and at no advance in cost of fences of its kind having the common smooth pickets. This improved ornamental fence will also ever present a clean and neat apperance, as all rain and other wa- 80 ter will run down the grooves or channels and off at the bottom, thereby washing the fence on all sides and down its entire surface, and preventing accumulations of dust, dirt, &c., at any point.

D designates the posts of my improved fence, which may be also channeled, if desired.

I am aware that fence-palings for use in wooden fences have been heretofore grooved for the passage of air for drying purposes, and 90 I therefore do not broadly claim a grooved picket.

In this class of fences pickets diamond shape or the like in cross-section are sometimes used, and these of course present a contact-point or 95 projecting portion at the center, against which the encircling twist of wire binds and can slightly enter; but in practice this central bearing-point only serves to the disadvantage of the fence, as this central bearing acts as a pivot 100 in sagging and does not possess bearing power sufficient to prevent vertical displacement. This single bearing-point soon becomes worn and the pickets work loose; but in my inven-

tion the pickets are entered by the wire to a greater extent and in a plurality of places on each side surface, which obviously prevents pivotal or vertical displacement. Pickets of 5 elliptical, ovolو, and like cross-section shapes present too great a smooth rounded surface to admit of the wire entering them at any point to obtain a hold in practical manufacture. When pickets rectangular or square in cross- 10 section are used the four points of the picket, two at each end, cannot be clamped by the encircling wire twists, as, owing to the position of the points and flat sides, it is impracticable in manufacture to clamp the twists into these 15 points, for the reason that sufficient purchase of the wire cannot be obtained, and the wire necessarily bulges out and over the surface of these rectangular pickets, this action of the wire increasing according to the thickness and 20 stiffness of the wire used. Besides, the neat, clean, and finished appearance necessary for ornamental fencing of this class cannot be secured with rectangular pickets having the wire bulging over their surfaces; but in pick- 25 ets of my construction, when the wire is not only enabled to enter the picket at a plurality of points on each side surface, but in which the shape of the picket also conforms to the bulging of the wire, neatness and efficiency,

with all other requisites of ornamental fencing 30 of this class, are secured.

It will also be observed that by means of the herein-described construction of picket, having the projecting ridges on all sides, and the encircling wire twists entering all of said 35 ridges, a mutual support is effected by which neither the pickets nor wires can in any manner be displaced.

I do not broadly claim a picket having contact-edges; but 40

What I do claim as my invention is—

As a new and improved article of manufacture, a picket-and-wire fence consisting of the pickets having a plurality of successive projecting ridges, the series extending around its 45 entire surface, with two or more of these ridges on each side surface, and having the encircling twists of the securing-wire entering and binding in all of said ridges to lock the picket on all sides firmly in position and obviate its displacement in any direction, as set forth.

In testimony that I claim the foregoing as my own I have hereto affixed my signature in presence of two witnesses.

WILBER THOMAS.
